UNITED STATES PATENT OFFICE

AUSTIN L. WERTZ, OF LAKewood, OHIO

DISPLAY DEVICE FOR DISPENSING PUMPS

Application filed March 20, 1930. Serial No. 437,380.

This invention relates to a display device adapted for attachment to liquid dispensing pumps and more particularly to a display device which is adapted for use with lubricant dispensing pumps of the type now in general use at automobile service stations.

The main object of the invention is to provide a device of the character described which may be quickly and readily attached to the outlet pipe leading from the dispensing pump for the purpose of giving a visual indication of the quality of liquid dispensed through the pump.

A further object of the invention is to provide a display device of the character described which is so constructed and arranged that the liquid dispensed from the pump must pass through the display chamber.

Another object of the invention is to provide a display device which is economical of fabrication, readily assembled and disassembled and well adapted for quantity production at comparatively low cost.

Further and more limited objects of the invention will appear as the description proceeds and by reference to the accompanying drawing in which Fig. 1 is a vertical sectional view of a display device constructed in accordance with the preferred embodiment of my invention and Fig. 2 is a horizontal sectional view on the line 2—2 of Fig. 1.

Referring now to the drawing, the numeral 1 designates the base member which is preferably cast in one piece. The base member 1 is shaped as shown most clearly in Fig. 1 and is provided with an inlet bore or passageway 2 and an outlet bore or passageway 3. The inlet passageway is preferably internally threaded and adapted to be attached to a discharge pipe 4 leading from the dispensing pump. The outlet passageway 3 is provided with an enlarged portion 5 constituting a valve chamber and the upper end of this enlarged portion is shaped to provide a valve seat. The lower or delivery end of the outlet passageway is internally threaded and adapted to receive therein an anti-drip nozzle 6. Arranged within the valve cham-

ber 5 is a ball valve 7 which is held against the valve seat by a coil spring 8, the lower end of which rests on the upper end of the anti-drip nozzle 6. The upper end of the outlet passageway 3 is somewhat L-shaped in cross section so as to provide an overhanging portion 9 having a threaded opening 10 therein, the purpose of which will hereinafter appear. The upper side of the base member is provided with an upstanding annular peripheral flange 11 which receives therein a glass cylinder 12 as shown most clearly in Fig. 1. A hollow tubular member 13 is threadedly secured in the opening 10 and extends axially through the glass cylinder 12. A cap 14 fits over the upper end of the glass cylinder and is provided with a centrally disposed opening 15 through which the tubular member 13 extends. The upper end of the tubular member 13 is externally threaded to receive a nut 16 which is tightened to securely clamp the glass cylinder 12 between the cap and base member. The upper end of the tubular member 13 is closed by a threaded cap 17; and the tubular member is also provided with a vent opening 18, the purpose of which will hereinafter appear. The delivery end of the inlet passageway 2 is preferably crescent shaped as shown in Fig. 2 and the intake end of the outlet passageway 3 is similarly shaped, the purpose of which will also hereinafter appear. The upper end of the inlet passageway 2 is also slightly inclined as shown at *a* in Fig. 1 so that the liquid discharged into the glass cylinder will be directed upwardly and toward the opposite side of the cylinder. The liquid is discharged into the glass cylinder through the inlet passageway with considerable force due to the relative size of the delivery end of the passageway with respect to its inlet end.

The display device is attached to the pipe 4 as hereinbefore described and for the first filling operation the cap 17 is removed and the pump operated to discharge liquid into the glass cylinder 12 until the same becomes filled with liquid. The air within the cylinder 12 escapes through the vent opening 18

and out through the open upper end of the tubular member 13. After the device is once filled the cap 17 is replaced and the cylinder remains filled with liquid. When the 5 pump is operated to dispense liquid, the liquid enters through the inlet passageway 2 and is discharged into the cylinder 12 at an angle with respect to the vertical axis of the glass cylinder. The pump is operated until 10 sufficient head has been built up to open the valve 7 against the tension of the spring 8 whereupon the liquid is discharged through the outlet passageway and anti-drip nozzle 6. The particular arrangement and shape 15 of the inlet and outlet passageways and the location of the same with respect to the vertical axis of the glass cylinder 12 gives the liquid a swirling motion during the dispensing operation, which swirling motion has the appearance of the figure 8.

It will be noted that the display container is always in open communication with the pump and that any liquid discharged through the device must pass through the display container and the particular arrangement and construction hereinbefore described provides for a very pleasing and attractive display and at the same time gives to the customer a visual indication of the 25 quality of lubricant which he is obtaining. The device as a whole is simple in construction, comprises comparatively few parts and is readily assembled and disassembled.

While I have described my invention with 30 reference to a lubricant dispensing device, it is obvious that the device is equally well adapted for use in connection with any liquid in which it is desired to display or to give a visual indication of the quality of the 35 liquid to be dispensed. Various changes may be made in the details of my construction without departing from the spirit of my invention and I wish my invention to be limited only in accordance with the scope 40 of the appended claims.

Having thus described my invention, what I claim is:

1. A display device for dispensing pumps comprising a transparent container having 50 a pair of oppositely disposed openings in the base thereof, said base having a bore connected with one of said openings and leading through said base and adapted for connection with the discharge side of a pump, the delivery end of said bore being disposed 55 at an angle to the vertical axis of said transparent container, and a second bore connected with the other of said openings and leading through said base and constituting a discharge outlet, and a spring seated valve 60 normally closing said discharge outlet and adapted to be opened by the pressure of the liquid in said container whereby the liquid delivered into said container will be given a 65 swirling motion.

2. A display device as set forth in claim 1 in which the openings in the base of said container are substantially crescent-shaped.

3. A display device of the character described comprising a base member, a transparent cylinder supported on said base member and having a vent opening in the upper end thereof, said base member being provided with a pair of oppositely disposed bores leading into opposite sides of said cylinder, one of said bores being adapted for connection with the discharge side of a pump, the other of said bores constituting a discharge outlet from said container whereby the liquid dispensed will flow through 70 said transparent container, a spring pressed valve normally closing said last mentioned bore and adapted to be opened by the pressure of the liquid therein, the delivery end of said first mentioned bore being substantially crescent-shaped and disposed at an angle with respect to the vertical axis of 75 said transparent cylinder whereby to give a swirling motion to the liquid within said container during the dispensing operation. 80

In witness whereof, I hereunto subscribe my name this 15th day of March, 1930.

AUSTIN L. WERTZ.
